UNITED STATES PATENT OFFICE

RICHARD VON EZDORF, OF ONEIDA, NEW YORK

DESIGN FOR A COMBINATION TELEPHONE STAND AND TELEPHONE BOOKHOLDER

Application filed July 30, 1932. Serial No. 44,501. Term of patent 3½ years.

To all whom it may concern:

Be it known that I, RICHARD VON EZDORF, a citizen of the United States, residing at Oneida, county of Madison and State of New York, have invented a new, original, and ornamental Design for a Combination Telephone Stand and Telephone Book Holder of which the following is a specification, reference being had to the accompanying drawing, form a part thereof.

I claim:—

The ornamental design for a combination telephone stand and telephone book holder as shown.

RICHARD VON EZDORF.
